UNITED STATES PATENT OFFICE.

FRANK EDWARD LICHTENTHAELER, OF NEWTON HIGHLANDS, MASSACHUSETTS.

LIQUID-LIFT.

1,279,558.

Specification of Letters Patent. Patented Sept. 24, 1918.

Application filed August 13, 1917. Serial No. 185,951.

To all whom it may concern:

Be it known that I, FRANK EDWARD LICHTENTHAELER, a citizen of the United States, residing at Newton Highlands, in the county 5 of Middlesex and State of Massachusetts, have invented certain new and useful Improvements in Liquid-Lifts; and I do hereby declare the following to be a full, clear, and exact description of the invention, such as 10 will enable others skilled in the art to which it appertains to make and use the same.

This invention relates to liquid lifts, and more particularly to lifts for elevating corrosive liquid chemicals from a lower to a 15 higher level.

The ordinary types of pumps used for elevating liquids are usually driven by some form of a motor, and the pump as well as the motor require constant attention while 20 operating. Further, pumps cannot be used advantageously for pumping many corrosive chemicals, such as concentrated acids and bases, because the liquids destroy the linings and parts of the pumps.

25 The primary object of the present invention is to provide an improved liquid lift which is simple in construction, efficient in operation, and which may be continuously operated without requiring the attention of 30 an operator.

Another object of the invention is to provide an improved, float-controlled mechanism for operating a valve, by which the valve will be effectively opened and closed 35 when the liquid level in the float-receptacle rises and falls to definite levels.

With these and other objects in view, the invention consists in the improved liquid lift hereinafter described and particularly 40 pointed out in the claims.

The various features of the invention are 45 illustrated in the accompanying drawings, in which Figure 1 is a vertical sectional view, in elevation, of a liquid lift embodying the preferred form of the invention; Fig. 2 is a diagrammatic view showing one relation in which the improved liquid lift may be connected with the delivering and receiving containers; and Fig. 3 is a sectional view, in elevation, showing a modified form of float for operating the lift valves.

The liquid lift shown in the drawings 55 illustrating the preferred form of the invention is arranged to be operated by com-

pressed air to elevate liquids from a lower to a higher level. The liquid to be elevated is held in a delivering container 10 and flows by gravity through an inlet pipe 12 to the bottom of a lift receptacle 14. The 60 lift receptacle is vented to the atmosphere to permit the receptacle to be filled with liquid, and at the time the receptacle is filled, a float therein is operated to close the air vent and to operate an air pressure valve 16 65 to admit compressed air through an inlet 18 to force the liquid through an outlet pipe 20 up to a receiving container 22.

The lift receptacle 14, shown in Fig. 1, has a comparatively small liquid volume, 70 and is adapted to be placed in any position with relation to the container 10 in which the top of the receptacle is below the level of the bottom of the container. The materials of which the receptacle is constructed 75 depend upon the character of the liquid to be lifted, and are so selected that the parts will not be corroded by the liquid operated upon. A cover 24 is mounted on the top of the receptacle, and a valve chest 26 is secured to the top of the central portion of the cover, the joints between the receptacle cover and valve chest being pressure tight. A valve 28 is slidably mounted in the valve chest and is secured at its lower end to a 80 vent pipe 30 which carries a float 32. To vent the receptacle to the atmosphere so that liquid may flow by gravity from the container 10 into the receptacle, a series of openings 34 are formed in the lower end of 85 the valve chest. These openings 34 communicate with the valve 28 and are arranged to be connected with a series of ports 36 in the valve chest by means of a valve chamber 38. When the liquid has substantially 90 filled the receptacle, the float 32 rises and moves the valve 28 to shut off the ports 36 from the atmosphere, as shown in Fig. 1. While the receptacle is being filled with liquid, the float remains in its lowermost position, and the valve chamber 38 is positioned to place the openings 34 in communication with the ports 36. A gage 40 is mounted in the side of the receptacle to indicate the position of the liquid therein. 95

To force liquid out of the receptacle in a minimum time, and thus increase the capacity of the lift, high pressure air in a comparatively large volume is admitted through the inlet 18. The compressed air admitted 100 105 110

to the receptacle is controlled by the valve 16 which is operated through the float 32 in such a manner that the valve will be opened to force liquid out of the receptacle when it 5 becomes filled, and closed when the receptacle becomes empty to permit the receptacle to be again filled. The air inlet 18 is connected with the valve 16 by a pipe 42, and a valve 16 in turn is connected by means of a pipe 44 10 with any suitable source of compressed air. The valve 16 consists of a pressure cylinder 46, in which is slidably mounted a piston valve 48. The piston valve is operated by compressed air which is controlled through 15 the float valve 28. To this end, compressed air from a suitable source enters a pipe 50 connected with the valve chest 26, and is admitted through valve chambers 52 or 54 in the valve 28 to pipes 56 or 58 respectively, which are 20 connected at one end to the valve chest 26 and at their other ends to the opposite ends of the cylinder 46. When the valve chamber 52 is in position to bring the pipes 50 and 56 into communication, the piston 48 25 will be moved into position to admit pressure to the receptacle. This position is shown in Fig. 1. At this time the float is in elevated position, and the liquid is being forced out of the receptacle. As the piston 30 is shifted into this position, the air at the opposite end of the piston is exhausted through the pipe 58, the valve chamber 54, and out through an apertured plug 60 in a port 62 formed in the valve chest 26. The 35 apertured plug 60 operates to cushion the movement of the piston 48 in the cylinder 46. When the liquid is forced out of the receptacle, the float will fall and move the valve 28 to bring the pipes 50 and 58 into 40 communication through the valve chamber 54. The compressed air admitted through the pipe 58 will move the piston 48 to close the valve 16, and the air at the opposite end of the piston will be exhausted through the 45 pipe 56, the valve chamber 52, and out through an apertured plug 64 in a port 66 formed in the valve chest 26.

When the float 32 is raised to admit compressed air to force the liquid out of the receptacle, a gas containing member or container is used to increase the buoyancy of the float 32 to hold it in elevated position until the receptacle has been emptied. The gas retaining member consists of a bell, which 55 is formed by the lower side 68 of the float 32, and a downwardly extending wall 70, which is a continuation of the cylindrical wall of the float. The mouth of the bell opens close to the bottom of the receptacle 14, and the 60 bell is vented into the upper portion of the receptacle through the vent pipe 30 and openings 72, to permit the liquid to fill the bell as it flows into the receptacle. The pressure inlet pipe 18 extends upwardly into the bell, and when the float 32 is raised to oper-

ate the air valve 16, the incoming air strikes against the face 68 and assists in raising the float. As the float is moved upwardly, a valve 74 mounted in the upper end of the inlet pipe 18 comes into engagement with a 70 seat 76 in the lower end of the vent pipe 30 and closes the vent pipe so that the air from the pressure inlet has to escape around the lower end of the bell as the liquid is being forced out of the receptacle 14. The air 75 trapped in the bell increases the buoyancy of the float 32 and will hold the float in elevated position until the liquid level falls below the bottom of the wall 70, at which time the buoyancy of the float will be destroyed 80 so that the float will fall to close the valve 16 by means of the auxiliary valve 28 and open the atmospheric vents 36 in the valve chest 26.

In Fig. 3 is shown a modified form of 85 float for operating the valve 28. This float differs from the combined float 32 and gas-retaining member formed by the bell 68—70, in that the wall 68 of the bell is omitted. With this construction, air will be trapped 90 above the bottom of the vent pipe 30 as the liquid rises in the lift receptacle, and the trapped air will give sufficient buoyancy to the float to operate the valve 28 and close the air vent and operate the valve 16 at the time 95 the lift receptacle becomes filled with liquid. As the valve 28 is moved upwardly to operate the valve 16, the valve 74 will close the pipe 30 and the incoming air will be trapped 100 under the float and assist in holding the float 105 in upward position. While the compressed air is forcing the liquid out of the lift receptacle, the float will be held in elevated position until the liquid level has fallen below the bottom of the wall 70 and destroys 110 the buoyancy of the float. When the float falls, the vent pipe 30 will be opened and the incoming liquid will fill the float up to the level of the bottom of the vent pipe 30 and trap air in the float to establish its 115 buoyancy.

At the time the receptacle 14 is being filled by liquid from the delivering container 10, the outlet pipe 20 is shut off from the receptacle by a check valve 78. The check valve 115 78 is connected between the pipe 20 and the lower portion of the receptacle 14, and is closed by the pressure of the liquid in the pipe 20. When the compressed air is admitted to the receptacle 14, the inlet pipe 12 120 is shut off from the receptacle by a check valve 80. The check valve 80 is connected between the pipe 12 and the lower portion of the receptacle 14, and is operated to close the inlet by the internal pressure in the lift 125 receptacle.

The reciprocatory movements of the float 32 in operating the valve 16 to admit and cut off the air pressure from the receptacle 14, occur when the liquid level in the receptacle 130

has reached predetermined levels. The volume of liquid removed from the receptacle for each reciprocation of the float 32 is constant and may be readily determined so that the lift may be employed as a meter for determining the volume of liquid passing therethrough. A counter 82 is mounted on the upper end of the valve chest 26, and is connected with the upper end of the valve 28 in such a manner that each reciprocation of the float will be recorded.

The mechanism for controlling the valve for opening and closing the atmospheric vent and the compressed air valve is simple in construction and accurate in operation. With the construction outlined above a comparatively small float may be employed in the lift chamber and still effectively operate the valves. The use of a gas retaining member or bell in conjunction with a float provides a simple mechanism which will not get out of order. The gas retaining member does not decrease the liquid capacity of the lift receptacle, and the buoyant action of the retaining gas makes the action of the float positive. The variable buoyancy of the float serves as a convenient means for withholding the operation of the valves until the liquid level in the lift receptacle has fallen to a desired level.

The word "gas" as used in the claims, is intended to include any gaseous or vaporous substance, since many substances such as steam, flue gas or exhaust gases, might be used in place of compressed air force liquid out of the lift receptacle.

The preferred form of the invention having been thus described, what is claimed is:—

1. A liquid lift having, in combination, a pressure tight receptacle having a liquid inlet and a liquid outlet, a float in the receptacle, a bell attached to the float, means to vent the receptacle to the atmosphere, a vent between the bell and the interior of the receptacle, means operated by the float and bell to close the atmospheric vent, and means to supply gas to the bell to force liquid out of the receptacle.

2. A liquid lift having, in combination, a pressure tight receptacle having a liquid inlet and outlet, a movably mounted float in said receptacle, a bell attached to said float, a vent between the bell and the interior of the receptacle, an atmospheric vent in the receptacle arranged to be opened and closed by said float, a gas pressure inlet mounted in said receptacle opposite said bell, and means to admit gas through said inlet.

3. The combination of, a pressure tight receptacle having a liquid inlet and outlet, a gas pressure inlet in said receptacle, a float in said receptacle arranged to open and close said gas inlet, a container secured to said float constructed and arranged to trap gas when gas is admitted through said inlet and

means to vent the container while the gas inlet is closed.

4. The combination of, a pressure tight receptacle, a liquid inlet and outlet for said receptacle, a gas inlet for said receptacle, a valve for admitting gas through said inlet, a float operated by the liquid in said receptacle and arranged to actuate said valve, and a bell attached to the float arranged to trap gas admitted through said inlet, to increase the buoyancy of said float and maintain the valve in open position until the liquid level in said receptacle has fallen sufficiently far to destroy the buoyancy of said bell.

5. A liquid lift having, in combination, a pressure tight receptacle having a liquid inlet and a liquid outlet, a gas pressure inlet in said receptacle, means for opening and closing the gas inlet, including a gas retaining member arranged to trap gas when it is admitted through the gas inlet to force liquid out of the receptacle, and means for venting the gas retaining member when the gas inlet is closed.

6. A liquid lift having, in combination, a pressure tight receptacle having a liquid inlet and outlet, means to force liquid into said receptacle, a gas pressure inlet in said receptacle, a float in said receptacle arranged to control the admission of gas through the gas pressure inlet, and a gas retaining member arranged to trap gas when it is admitted through said inlet, to hold the float elevated and to maintain the gas inlet open until the liquid level in said receptacle has become sufficiently low to destroy the buoyancy of said member.

7. A liquid lift having, in combination, a pressure tight receptacle having a liquid inlet and outlet, check valves in said inlet and outlet, an atmospheric vent in said receptacle, a float in said receptacle arranged to open and close said vent, a bell secured to said float having its mouth positioned near the bottom of the receptacle, and a gas pressure inlet mounted in said receptacle and arranged to discharge into the mouth of said bell.

8. A liquid lift having, in combination, a pressure tight receptacle, a liquid inlet and outlet for said receptacle, a gas pressure inlet in said receptacle, an atmospheric vent in said receptacle, a float in said receptacle, means connected with the float for opening and closing the atmospheric vent and gas pressure inlet, a downwardly open bell secured to said float, a vent between said bell and the interior of the receptacle, and a valve arranged to close the bell-vent when the float is moved to admit gas to said receptacle.

9. A liquid lift having, in combination, a pressure tight receptacle having a liquid inlet and a liquid outlet, a float in the receptacle having a bell attached thereto opening

4
downwardly, a gas pressure inlet, vents for venting the receptacle and the bell when the gas inlet is closed to permit liquid to flow into the receptacle, and means controlled by 5 the float for closing the vents and opening the gas inlet to admit gas to the bell to force liquid out of the receptacle.

10. A liquid lift having, in combination, a pressure tight receptacle having a liquid inlet and outlet, means to force liquid into 10 said receptacle, a float in said receptacle comprising a downwardly open container closed on its upper side, a vent between the interior of the container and the interior of 15 the receptacle and located below the upper side of the container, a gas pressure inlet in said receptacle opening into said container, and means connected with the float

for controlling the admission of gas through 20 said inlet.

11. A liquid lift having, in combination, a pressure tight receptacle having a liquid inlet and outlet, means to force liquid into 25 said receptacle, a float in said receptacle comprising a downwardly open, closed top container, a vent pipe mounted in said container and projecting downwardly into the interior thereof to vent gas from the container into said receptacle, a gas pressure inlet in said receptacle opening into said 30 container, means connected with the float for controlling the admission of gas through said inlet, and a valve for closing said vent pipe when gas is admitted below said container.

FRANK EDWARD LICHTENTHAELER.
